UNITED STATES PATENT OFFICE.

JOHN CRAWSHAW, OF COBOURG, CANADA.

IMPROVEMENT IN HEDDLE-ACTUATING MECHANISMS.

Specification forming part of Letters Patent No. 129,718, dated July 23, 1872.

Specification describing a new and useful Improvement in Looms, invented by JOHN CRAWSHAW, of Cobourg, in the Province of Ontario and Dominion of Canada.

This invention has for its object to simplify the mechanism for producing the harness-motion in fancy and other looms. The invention consists chiefly in the use of vibrating bell-crank on a sliding frame, the cranks serving to vibrate the jacks, whereby the harness is raised and lowered. The harness is, by this arrangement, raised and lowered at one motion, where hitherto two have been usually required. The invention also consists in other improvements regarding the cam which turns the chain, the levers which reset the "jacks" and lower the harness after each stroke, and other details, as hereinafter more fully described.

In the accompanying drawing, Figure 1 represents a vertical longitudinal section of a loom containing my improvements. Fig. 2 is a top view, partly in section, and Fig. 3 a vertical transverse section of the same. Fig. 4 is a detail side view of the resetting-levers and their connection.

Similar letters of reference indicate corresponding parts.

A in the drawing represents the frame of the loom, on which the warp-drum, the winding-up drum, the batten, reed, tension, and shuttle devices are arranged, applied, and constructed in suitable manner. B is the shaft, whereby the harness mechanism receives its motion. This shaft hangs transversely in the frame A, and receives rotary motion by suitable connection. The heddles C C are suspended from cords a a, which pass over friction-rollers b b, and are attached to the upper ends of levers or "jacks" D D. These said jacks are hung side by side on a pin, d, which is supported horizontally at the side of the frame A. There is one jack, D, for every heddle, C. When the upper end of a jack, D, is swung away from the loom the heddle connected with it is thereby drawn up. The lower part of each heddle is, by a cord, e, which passes over a friction roller or rollers, f, connected with the lower end of one of a lower set of jacks, E E. These latter are hung side by side to a pin, g, which is supported horizontally at the side of the loom. It may be observed that the upper ends

of the jacks E are directly beneath and close to the lower ends of the jacks D, and further that the two jacks D E, which pertain to each single heddle, are in line with each other vertically. It is evident that a heddle will be drawn down whenever the lower end of the jack E with which it is connected is swung away from the loom. The requisite motion is imparted to the several jacks D E by means of elbow-levers or bell-crank F F, which hang on a pin, h, that is held in a horizontal sliding frame, G. This frame is moved back and forth by means of a crank-shaft, J, which is revolved by bevel-wheel connection i with the shaft B, the cranks of the shaft J entering forward projections of the frame G. The frame G carries also the upper chain-drum H, from which the chain I is suspended in the ordinary manner. The projections of the chain bear, as the drum H is gradually turned in their proper succession, against the vertical arms of the bell-crank F, and vibrate these cranks so as to elevate their horizontal arms. In their neutral position the horizontal arms of the bell-crank are in line with the upper ends of the lower jacks E. When the bell-crank are, however, vibrated by contact with the chain I the ends of their horizontal arms will be raised in line with the lower ends of the upper jacks D. It is evident that one bell-crank, F, is provided for every pair of jacks, D E. Whenever the frame G is, by the crank-shaft J, drawn toward the loom, those of its elbow-levers F, which are effected by the chain I, will bear against their respective upper jacks D and vibrate them so as to raise the heddles connected thereto. The remaining bell-crank will bear against the upper ends of their respective lower jacks E and draw the heddles connected therewith down. On the return move of the frame G—that is to say, when said frame moves away from the loom—the contact of the bell-crank with the jacks is terminated and the heddles are at liberty to resume their neutral, i. e., middle, position, which is neither entirely up nor down. In order to bring all heddles, on such return stroke of the frame G, to their middle or neutral position, two levers, L L', are pivoted at j l, respectively, to the frame A, one above the other, (see Fig. 4,) and lock together at their contiguous ends by tenon and socket m, as shown. By means of a projecting pin, n, one of these

levers, L, is connected with a rod, o, pivoted to an arm or lever, M, which is suspended at its upper end from the frame A. The lower part of the lever M is in contact with a cam, p, which is mounted upon the shaft J. The levers L and L' carry projecting arms r and s, respectively, behind the upper parts of the jacks D and the lower parts of the jacks E. When the frame G is on its return stroke to clear the jacks from contact with the bell-crank, as above mentioned, the cam p swings the lever M, and thereby also the levers L L', so that the latter will lay their arms r s against the jacks D E, respectively, and thereby swing the jacks back to their respective neutral positions, and draw the heddles all into line with each other—i.e., so that they are neither entirely up nor down. The jacks are then in position for the next contact with the bell-crank, which are changed by the chain during the return move of the frame G, or at the end of the return move, while the bell-crank are not in contact with the jacks. Thus it will be seen that one rotation of the crank-shaft J, producing a back-and-forward motion of the frame G and a vibration of the levers L L', will suffice to move the heddles in advance of and subsequent to a shuttle movement. The mechanism is very simple and positive in its action, and under complete control. The chain-drum H receives its intermittent rotary motion by means of a worm, t, which is attached to a sleeve, u, embracing a shaft, N. This shaft N, hanging in bearings that project from the frame G, moves back and forth with the latter, and slides meanwhile through the gear-wheel v, which gives it rotary motion. The gear-wheel v matches into another toothed wheel, w, on the shaft B, and is, by feather and groove, connected with the shaft N to revolve the same during the reciprocating motion of the frame G. The worm t enters a notched disk, x, which is mounted upon the

end of the drum H, and turns the disk and drum by passing gradually from notch to notch, one revolution of the shaft N producing one change of notch to notch, and a consequent partial turn of the chain. The sleeve u is, by a spring, (not shown,) held with a notch in its end against a pin, y, which projects from the shaft N, as shown in Fig. 3. When from any cause the drum H does not turn with proper ease, so that its attempt to remain at rest will overcome the power of the concealed spring, the shaft N will carry its pin y out of the notch in the sleeve, crowding the sleeve back against the spring, and will revolve without affecting the position of the spring. The drum H will, in that case, not be turned.

Having thus described my invention, I claim as new and desire to secure by Letters Patent—

1. The bell-crank F F, hung in the reciprocating frame G to actuate the jacks D E and the loom-harness, substantially as herein shown and described.
2. The interlocking vibrating levers L L', provided with the projecting arms r and s to return the jacks D E and the heddles to their neutral position, arranged and operated as specified.
3. The crank-shaft J, combined with the reciprocating frame G and with the levers L L' to actuate them, substantially as herein shown and described.
4. The rotary reciprocating shaft N for carrying the adjustable sleeve u for turning the chain-drum, and the pin y for locking said sleeve, substantially as herein shown and described.

JOHN CRAWSHAW.
